UNITED STATES PATENT OFFICE

ALEXANDER F. BATCHELLER, OF HAWARDEN, IOWA.

CORN-HARVESTER.

SPECIFICATION forming part of Letters Patent No. 512,999, dated January 16, 1894.

Application filed March 23, 1893. Serial No. 467,369. (No model.)

To all whom it may concern:

Be it known that I, ALEXANDER F. BATCHELLER, a citizen of the United States, and a resident of Hawarden, in the county of Sioux and State of Iowa, have invented certain new and useful Improvements in Corn-Harvesters; and I do declare the following to be a full, clear, and exact description of the invention, such as will enable others skilled in the art to 10 which it appertains to make and use the same, reference being had to the accompanying drawings, and to letters of reference marked thereon, which form a part of this specification.

15 Figure 1 is a side elevation of the harvester. Fig. 2 is a similar view, taken from the opposite side. Fig. 3 is a plan view of the harvester. Fig. 4 is a section on the line $x-x$, Fig. 3. Fig. 5 is a section on the line $y-y$, Fig. 3. Fig. 6 is a vertical section on the line $w-w$, Fig. 1. Fig. 7 is a detail perspective view of a portion of the frame and guides. Figs. 8 and 9 are detail views of a portion of the driving gear in different positions. Fig. 20 10 is a detail view of two of the saws. Fig. 11 is a detail view of a portion of one of the feeder chains or carriers. Fig. 12 is a plan view of the steering gear.

This invention has relation to certain new 30 and useful improvements in corn harvesters, the object being to provide a machine of improved character which will gather the ears from the standing corn in the field; and the invention consists in the novel construction 35 and combination of parts, all as hereinafter described and pointed out in the claims.

Referring to the accompanying drawings, the letter A designates the main frame of the machine, which is inclined upward from its 40 forward to its rear end, at an angle of about forty five degrees to the horizontal. Near its lower forward end, said frame carries a short, laterally projecting axle stud or journal a, upon which is journaled the main supporting 45 and drive wheel B. From the opposite side of the frame, at a point higher than that of the journal a, there projects laterally at right angles an arm C, which is extended to a considerable distance from the body of the frame, 50 and terminates in a downward and forwardly curved arm C', which at its lower portion car-

ries a stud or journal b, upon which is journaled the supporting wheel B'. Said arm C' is connected to the rear upper portion of the frame by a brace C². The arm C also has a brace C³ to the body of the frame. The main portion of the frame consists of three parallel inclined bars A', which are separated from each other sufficiently to permit the passage of the corn therebetween, and the operation of the picking saws as hereinafter described. Journaled in each of these three bars is a series of short transverse shafts c. In the machine illustrated, there are three of these shafts in each series, corresponding 65 shafts in each series being arranged in transverse alignment. The shafts c of the middle bar, at their central portions carry each a toothed wheel c', the bar being cut away as shown to permit the rotation of these wheels 70 therein with their shafts. The shafts c of each outer or lateral bar carry similar wheels, but they are placed upon the outer ends of the shaft. Each series of these wheels c' carries an endless sprocket chain D, which passes 75 over said wheels, around the ends of the bar and under said wheels, and at the upper rear portion of the frame at the upper ends of said bars A', is journaled a transverse shaft E, which carries three toothed wheels d, similar 80 to the wheels c', one of said wheels d being in alignment with each series of the wheels c'. The chains D also pass over these wheels d which form the driving wheels for said chains, power being transmitted to the shaft 85 E by a longitudinal inclined shaft F, located outside the frame, and having a bevel wheel F' at its lower end, which meshes with an annular bevel gear wheel F² on the drive wheel B. On the upper end of the shaft F is also a 90 bevel gear wheel F³, which gears into a similar but smaller wheel F⁴ on the shaft E. On each end of each of the shafts c' of the middle bar, and on the inner end of each shaft c' of the lateral bars is a large toothed disk 95 or saw G, having long hooked teeth f.

Above the outer edge of each of the lateral bars A' is secured a guard plate G', the lateral sprocket chains D running one between each of said guard plates and the lateral series of saws, and the central chain between the two central series of saws. Above said

saws the guard plates G^2 are secured to the inner edge of each lateral bar A' , and to both edges of the central bar, so that each chain is provided with a laterally closed passage 5 through which it works. Each chain is provided at intervals with projections or teeth g , so that it forms an endless carrier for the ears which are broken off by the saws, as presently described, the guards G' G^2 and the saws, 10 which form the passages through which said carriers work, as above described, preventing the ears from falling through the frame.

Supported above the main frame A is a second parallel frame A^2 , comprising the two 15 parallel side portions a^2 , the upper rear cross piece a^3 , and the upward bow portion a^4 , which is connected to the cross piece a^3 , by the brace a^5 .

Secured to the upper portion of the bow portion a^4 at each side is a bracket g' , and in these brackets is journaled a transverse shaft H , which carries near each end a bevel gear wheel H' , each of which gears into a similar wheel H^2 on the upper portion of a vertical shaft H^3 . Said shafts H^3 are journaled at their lower portions one in each side portion a^2 of the frame A^2 , and at their upper portions in arms of the brackets g' . Each of said vertical shafts H^3 carries at its intermediate 25 portion, two sprocket toothed wheels I , the lower of said wheels being a short distance above the saws, while the upper wheel is considerably above the saws.

At the forward end of the machine are two shafts J , J , which are parallel with the shafts H^3 , one of said shafts J being journaled at its lower end at each lower forward side portion of the main frame, and at its intermediate portion in a bearing h carried by the 30 arms a^6 of the frame A^2 . Each shaft J carries two sprocket toothed wheels J' , each of which is placed at about the same relative distance above the saws, as the corresponding wheels I on the shafts H^3 . Each pair of said 35 wheels I and J , on the same side of the machine carry an endless sprocket chain or belt J^2 , similar to the carriers D before described and having projecting spring teeth or fingers. This arrangement, it will be apparent from 40 the above description, and from the drawings, provides each side of the machine with a pair of these endless chains or belts, the plane of whose travel is parallel to the inclined plane of the frame. The purpose and operation of 45 these chains will hereinafter appear. The shaft H is driven by a sprocket chain K from the shaft E , and the arrangement of the gear is such, that the inner portions of the chain carriers J^2 are caused to travel from front to 50 rear, or in the same direction as the upper portions of the carriers D .

At the upper rear portion of the frame A is arranged a platform L , onto which the ears of corn are designed to be discharged by the carriers D . Said platform is inclined downwardly toward the left hand side of the ma-

chine where it joins a vertical chute L' , down which the ears pass from said platform.

Leading upwardly and laterally from the lower portion of the chute L' is a chute or trough M , through which travels in an upward direction one portion of an endless carrier or conveyer belt or chain M' , which passes over a carrying wheel l , at the upper portion of said chute or trough, its other portion passing downwardly under the chute or trough to the lower end, where it passes over the driving wheel m in the lower portion of the chute L' . The driving wheel m is carried by a short shaft m' , having a bevel gear wheel m^2 , 80 which gears into a wheel m^3 on a second short shaft n at right angles to the shaft m' . Said shaft n is driven by the chain K from the shaft E said chain passing over a gear wheel n' on said shaft, (see Figs. 1, 2, 4 and 5) or by other 85 suitable connection. The chute L' is connected to the arm C by a brace N .

O designates the pole which at its forward end is connected to the frame A shortly in rear of the wheel B , and but a short distance 90 inside of said wheel. Said pole is extended horizontally rearward to a considerable distance to the rear of the main portion of the machine, and is braced to the rear upper portion of the machine by a downward arm O' of the 95 frame A . The rear portion of said tongue is supported upon a guide wheel P , journaled in a bracket P' , the post p of which is swiveled in said tongue, and carries at its upper portion a toothed crown segment Q , the teeth of 100 which gear into the teeth of a segment Q' , on the lower arm of a steering lever R , which is fulcrumed to a brace R' on the tongue. R^2 is the seat, supported on said tongue, and R^3 a foot rest. By the operation of the lever R 105 it will be apparent that the machine may be guided as may be desired.

In order that the shaft E , and thereby the entire operating mechanism of the harvester may be thrown out of gear when desired, the bevel gear wheel F^2 on the shaft F , which gears into the wheel F^3 on the shaft E , as hereinbefore described, is made capable of an endwise movement on the shaft F , and is connected thereto by a pin o , and slot o' . 110 Said wheel F^2 is also formed with a grooved collar or boss o^2 , the groove of which is engaged by the curved upper portion of an arm S , pivoted at its lower portion to the arm O' of the frame A . Connected to said arm S and to the frame is a spring S' , the tension of 115 which is such as to normally hold the wheel F^2 in engagement with the pin o of its shaft. Connected also to the arm S is a cable S^2 , which extends rearwardly along the tongue, 120 passing through a guide s thereon, and at its rear end connected to a pivoted or rocking foot lever S^3 within reach of the seat. When 125 said lever is depressed, a tension is given the cable S^2 , which acts on the arm S and the wheel F^2 to throw the latter out of connection 130 with its shaft.

T designates the draft attachment which is connected to the pole shortly in front of the seat.

The operation of the machine will now be described in detail. The machine is so placed that its lateral bars A', will straddle a row of corn, the stalks of which will be guided in between said bars and the central bar, by means of the front lateral guides U, projecting forwardly from the frame, and by the center guide U', from which extends upwardly and rearwardly a rod or bar V, which extends longitudinally of the machine over the central carrier D at about the height of the lower lateral carriers J², and is connected at its rear upper portion to the brace a⁵. Rods V' also extend back from the center guide and from the lateral guides, between the lateral and central bars A', said rods being connected to the frame at their forward ends. As the machine progresses, the stalks are forced in between the rods V', and between the chain or belt J² and the central rod or bar V, said chains or belts acting as feeders and catching the upper portions of the stalks, bringing them in, and holding them in position for the saws to act. The lower ears on the stalks will come under the action of the lower saws early in the passage of the corn through the machine, the higher ears coming under the action of the upper saws. These saws strike the ears, breaking them from the stalks, and they fall upon the endless chain carriers D, and are carried up and deposited upon the platform L. From this platform they fall into the chute L', when they are taken up the trough or chute M by the carrier M'. From the upper end of the chute or trough the ears fall into a suitable vehicle, which is driven alongside of the harvester. The stalks after having been deprived of their ears, pass under the upper portion of the machine to the rear. It will be understood that the machine is drawn in such a manner that the discharging chute or trough M overhangs that portion of the field where the corn has been picked by the previous passage of the machine.

It will be obvious that I may vary the construction of the various frame pieces, and other minor parts of the machine from that herein shown and described, without departing from the spirit and scope of the invention.

Having described this invention, what I claim, and desire to secure by Letters Patent, is—

1. In a corn harvester, the combination with an inclined frame, of a series of saws journaled at different heights in an inclined plane on said frame, the endless carriers, the mechanism for guiding and bringing the corn to said saws, and the driving mechanism, substantially as specified.

2. In a corn harvester, the combination with an inclined frame, of a series of vertical saws journaled at different heights in an inclined

plane on said frame, the endless carriers, the endless lateral feeder chains or belts, and the driving and delivering mechanism, substantially as specified. 70

3. In a corn harvester, the combination with an inclined frame having a series of inclined bars, a series of short shafts journaled transversely in said bars, toothed disks or saws, 75 carried by said shafts, endless carriers traveling between and laterally of said saws, mechanism for driving said carriers and saws, the guides for causing the corn to enter between said bars, the lateral endless revolving feeder chains, and the carrying and driving gear therefor, substantially as specified. 80

4. In a corn harvester, the combination with several series of rotary saws or disks journaled at different heights on horizontal axes 85 in an inclined plane, of a series of endless traveling feeders having teeth or projections thereon, and arranged to bring the corn into position to be operated upon by said saws, substantially as specified. 90

5. In a corn harvester, the combination with the inclined frame, having a series of parallel bars forming passages for the corn between them, the short shafts journaled in each of said bars in different horizontal planes, the 95 toothed wheels carried by said shafts, the endless carriers carried by said wheels, the toothed disks or saws on said shafts, the lateral feeder chains or belts, and the driving gear, substantially as specified. 100

6. In a corn harvester, the combination with the inclined main frame, the saws, journaled at different heights on horizontal axes in an inclined plane and the endless carriers working in close relation to said saws, of the upper frame supported upon and parallel with said main frame, the vertical shafts journaled therein, the gear wheels on said shafts, the endless belts or chains carried by said gear wheels and traveling in a plane parallel 105 to said frame, and the driving gear, substantially as specified. 110

7. In a corn harvester, the combination with the inclined frame, its parallel bars having passages between them, the short shafts journaled in said bars, the toothed wheels on said shafts, the toothed disks or saws also on said shafts, the endless carriers working between and laterally of said saws, the laterally closed passages through which said carriers work, 115 the delivery platform, the chute therefrom, and the conveyer traveling through the lower portion of said chute, substantially as specified. 120

8. In a corn harvester, the combination with a series of rotary toothed disks or saws, and their driving mechanism, and means for bringing the corn under the action of said saws, of a series of endless carriers working between and laterally of said saws, guard plates 125 in connection with said saws to form laterally closed ways for said carriers, a platform onto which said carriers are arranged to discharge, a chute from said platform, and an elevating 130

conveyer working through the lower portion of said chute, substantially as specified.

9. In a corn harvester, the combination with a frame inclined from its forward end upwardly, and having a series of parallel bars forming corn passages between them, a series of short shafts journaled in each of said bars, a double series of toothed disks or saws carried by the central series of said shafts, a single series of saws carried by each lateral series of said shafts, an endless carrier working between said double central series of saws and laterally of each lateral series, the driving mechanism for said carriers and saws, and means for bringing the corn to the action of said saws, substantially as specified.

10. In a corn harvester, the combination with the inclined frame, its supporting wheels, the saw shafts and saws, the toothed wheels on said saw shafts, and the endless chain carriers gearing on said toothed wheels, of the transverse shaft journaled at the upper rear portion of said frame, the toothed wheels thereon, into which said chain carriers gear, the inclined longitudinal shaft geared to the driving wheel, and bevel gear on the upper end of said shaft driving similar gear on said transverse shaft, substantially as specified.

11. In a corn harvester, the combination with the frame inclined from its forward edge upward, its parallel bars A' forming corn passages between them, and the rotary saws and endless carriers working on said frame, of the lateral and central guides at the forward portion of said frame, the rods running from said guides between said bars A', the upper central rod V, and the traveling endless feeder chains or belts working above said saws, substantially as specified.

12. In a corn harvester, the combination with the inclined frame, the saws, the saw shafts and gear, the endless carriers D, the transverse shaft E, its gear, the upper parallel frame A², its upward bow, the transverse shaft journaled upon said bow, its driving gear from the shaft E, its bevel gear wheels, the vertical shafts driven by said bevel gear, the parallel vertical shafts at the lower forward portion of the frame, the toothed wheels on said vertical shafts, and the endless chains or belts carried by said toothed wheels, said belts or chains traveling in a plane parallel with that of the inclined frames, and having teeth or projections thereon, substantially as specified.

13. In a corn harvester, the combination with the inclined frame, the saws, and the endless carriers traveling alongside said saws, of the platform at the upper rear portion of

the frame upon which said carriers discharge, 60 the chute leading downward from one edge of said platform, the trough projecting upwardly and laterally from the lower portion of said chute, the elevating conveyer working in said trough, its carrying mechanism and driving 65 gear, substantially as specified.

14. In a corn harvester, the combination with a series of rotary toothed disks or saws, working in vertical planes and journaled in different horizontal planes, but in the same 70 oblique plane of a series of endless traveling belts or chains having hooks or projections thereon and arranged to bring the corn to the action of said saws, substantially as specified.

15. In a corn harvester, the combination 75 with a series of rotary toothed disks or saws working in vertical planes and journaled in different horizontal planes, and mechanism for bringing the corn to said saws, and a series of endless carrier chains working in proximity to said saws, and traveling in the inclined plane thereof, substantially as specified.

16. In a corn harvester, the means for breaking the ears from the stalks, comprising a series of rotary, toothed disks, or saws, working in vertical planes and journaled in different horizontal planes, substantially as specified.

17. A corn harvester, comprising essentially the supporting and guide wheels, the inclined 90 frame thereon, the series of rotary saws working in vertical planes and journaled in different horizontal planes on said frame, the endless conveyers which carry the ears from said saws, the guides and traveling belts or chains 95 for bringing the corn to said saws, and the driving mechanism, substantially as specified.

18. A corn-harvester comprising essentially the supporting wheels, the inclined frame thereon, the series of rotary saws in said frame 100 working in vertical planes and journaled in different horizontal planes, the guides and endless traveling belts or chains which bring the corn to said saws, the endless conveyers and chutes for carrying the ears away from 105 the saws, and delivering them off the machine, the rearwardly extended pole, the guide wheel and its operating mechanism, and the foot-lever operated devices for throwing the driving mechanism out of gear, substantially as 110 specified.

In testimony whereof I affix my signature in presence of two witnesses.

ALEXANDER F. BATCHELLER.

Witnesses:

J. O. DUNCAN,
G. F. HUNTER.
